UNITED STATES PATENT OFFICE

163,766

COMBINED CAMERA AND SUPPORT
THEREFOR

Gustave Reamer, Baltimore, Md.

Application January 15, 1951, Serial No. 13,807

Term of patent 14 years

(Cl. D61—1)

To all whom it may concern:

Be it known that I, Gustave Reamer, a citizen of the United States of America, residing in the city of Baltimore, State of Maryland, have invented a new, original, and ornamental Design for a Combined Camera and Support Therefor, of which the following is a specification, reference being had to the accompanying drawings, forming part thereof.

Figure 1 represents a front elevation of the combined camera and support therefor.

Figure 2 represents a plan view.

Figure 3 represents a side view.

I claim:

The ornamental design for a combined camera and support therefor, as shown.

GUSTAVE REAMER.
